United States Patent Office.

WILLIAM HOFER, OF NEW HAVEN, CONNECTICUT.

Letters Patent No. 91,634, dated June 22, 1869.

IMPROVEMENT IN SCREW-DRIVER.

The Schedule referred to in these Letters Patent and making part of the same.

To all whom it may concern:

Be it known that I, WILLIAM HOFER, of New Haven, in the county of New Haven, and State of Connecticut, have invented a new and useful Improvement in Screw-Drivers; and I do hereby declare that the following is a full, clear, and exact description thereof, which will enable others skilled in the art to make and use the same, reference being had to the accompanying drawing, forming part of this specification, in which the figure is a detail sectional view of my improved screw-driver.

The object of my invention is to effect certain improvements in the construction of that class of screw-drivers whose bits are caused to rotate by pressure applied to their handles; and

It consists in the construction and combination of the various parts of the tool, as hereinafter more fully described.

A is the handle of the screw-driver, which is perforated longitudinally from its forward end, nearly to its other end, as shown in the figure.

B is a tube, fitting into the perforation of the handle A, and kept from revolving in said handle by means of longitudinal flanges formed upon its sides, which enter longitudinal grooves in the interior surface of the handle A.

The tube B is slotted spirally, with two spiral slots, extending nearly from end to end of said tube.

C is the bit of the screw-driver, the shank of which enters and fits into the tube B.

Through the inner end of the shank of the bit C, is passed a pin, c', the ends of which enter and move back and forth through the slots in the tube B, as the shank of the bit C moves back and forth in the said tube B.

D is a coiled-wire spring, the inner end of which rests against the handle A, at the inner end of the perforation in said handle, and its outer end rests against the inner end of the shank of the bit C, or against a circular plate attached to the end of said shank.

E is a wire spring, coiled around the shank of the bit B, and the inner end of which rests against the pin c' of the bit-shank C, when the bit is drawn out.

The outer end of the spring E rests against the cap F, attached to the forward end of the handle A, as shown in the drawing.

By this construction, when the bit C is placed in the slot in the head of the screw, and the handle A is forced downward or forward, the shank C will be revolved, and drive the screw into the wood, and when the pressure is removed from said handle, the elasticity of the coiled spring D will revolve the handle A back to its former position, so that the screw may be forced further in, by again pressing down upon the said handle.

For convenience in holding the bit C to its place in the head of the screw, while the handle A is allowed to revolve back, I provide a ring, a', which is arranged on the lower portion of the handle A, and held in place by the ferrule H, secured upon the handle in any suitable or preferred manner. By holding the said ring with the thumb and fingers, the handle A may revolve back, while the bit C is held in place without removing the hand from said handle A.

In the sides of the tube B, at the outer ends of the slots in said tube, are formed notches b', into which, when the bit C is drawn fully out, the pins c' are forced and held by the elasticity of the spring E, forming a long screw-driver with a stationary bit, with which screws may be turned in or out, in the ordinary manner.

In the tube B, near the inner ends of the slots in the said tube, are formed notches b'', into which the pins c' may be allowed to enter, and in which they are held by the elasticity of the spring D, forming a short screw-driver with a stationary bit, with which screws may be turned in or out, when only a slight forward pressure is required to be applied to said screws.

I am aware of the patent granted to Isaac Allard, August 4, 1868, but as the same constitutes no part of my invention, I claim nothing therein shown.

What I do claim, and desire to secure by Letters Patent, is—

The combination, with the handle A, of the ring a', spirally-slotted tube B, springs D and E, cap F, and bit C c, provided with the pin c', by which said bit is adapted to be rotated, and also to be locked at the respective ends of the tube in the notches b'', all constructed, arranged, and operating as set forth.

WILLIAM HOFER.
